UNITED STATES PATENT OFFICE.

JOHN W. SMITH, OF ERIE, PENNSYLVANIA, ASSIGNOR TO BALL ENGINE COMPANY, OF ERIE, PENNSYLVANIA, A CORPORATION OF PENNSYLVANIA.

STEAM-TURBINE.

No. 823,447.

Specification of Letters Patent.

Patented June 12, 1906.

Application filed January 26, 1903. Serial No. 140,555.

To all whom it may concern:

Be it known that I, JOHN W. SMITH, a citizen of the United States, residing at Erie, in the county of Erie and State of Pennsylvania, have invented certain new and useful Improvements in Steam-Turbines; and I do hereby declare the following to be a full, clear, and exact description of the invention, such as will enable others skilled in the art to 10 which it appertains to make and use the same.

This invention relates to improvements in steam-turbines.

Steam expanding from a higher to a lower 15 pressure reaches a velocity in proportion to the difference in pressure, and it therefore follows that if the expansion is carried out in several separate steps the ratio of expansion will be diminished, thereby diminishing in 20 turn the velocity at which the steam flows.

In the usual construction of steam-turbines it is customary to admit the steam to the rotating element and wholly expand the same at one point of impact only. Consequently 25 the steam expanding wholly at this one point imparts a very high rotation to the movable element. At the same time by reason of the steam expanding only at one point the remaining portions of the rotating element are idle, so far as the action of the steam 30 is concerned, until the same arrive opposite the point wherein the steam is admitted, at which point these portions are subjected to the expansion of the steam as it continues to 35 flow from the boiler, in order that the rotation of the movable element may continue.

It is therefore the object of the present invention to improve the general construction 40 of steam-turbines by including therein a simple yet very efficient arrangement whereby the steam, in lieu of becoming wholly expanded at a single point is caused to be expanded at a series of points and in a series of successive steps around the periphery. For 45 this purpose it is necessary to divide the periphery at several points which requires the construction of a turbine of comparatively large diameter, but by the same is attained a reduction in the peripheral speed through the 50 series of expansions, and also a reduction by means of the large diameter of the rotary speed. The rotary element thus receives the

full expansive force of the steam at various points thereon and without being caused to move at an excessively high rate of speed.

A further object of the present invention is to embody in the construction of a steam-turbine simple and efficient means for continuously superheating the steam as the latter passes through the successive steps of expansion, thus insuring the greatest degree of economy, and also to provide an improved construction whereby the rotating element under the heat to which it is subjected during the passage of the steam may readily expand and contract without injury to the machine.

A further object of the present invention is the provision of a novel form of joint between the rotating element and stationary elements, the use of which effectually eliminates escape or leakage of the steam as it passes successively through said elements, and by which outward pressure in the spaces adjacent to said elements is entirely eliminated.

A further object of the invention is to produce high efficiency under light load as well as full load by means of admitting the steam to the machine through two or more inlets.

With these general objects in view and others which will appear as the nature of the improvements is better understood the invention consists, substantially, in the novel construction, combination, and arrangement of parts, as will be hereinafter fully described, illustrated in the accompanying drawings, and pointed out in the appended claims.

In the drawings, Figure 1 is a side elevation of a steam-turbine constructed in accordance with the present invention. Fig. 2 is a face elevation thereof viewing the machine from the inlet side. Fig. 3 is a sectional elevation on the line 3 3, Fig. 1. Fig. 4 is a vertical transverse sectional view on the line 4 4, Fig. 2. Fig. 5 is a sectional diagrammatic view illustrating the relation of the rotating element to the admission and release blades and the receiving and return chambers. Fig. 6 is a fragmentary elevation of the rotating element and the blades carried thereby. Fig. 7 is a detail sectional view of another form of the invention illustrating the use of a plurality of blades in con-

junction with the movable element. Fig. 8 is a diagrammatic sectional view of the construction disclosed in Fig. 7.

Referring to the drawings, the numeral 1 designates the shaft of the herein-described turbine upon which is mounted a disk 2, the latter constituting the body of the movable element and being of sufficient diameter to adapt the machine for generating the desired power.

The body of the machine comprises a casing 3, which casing is formed of two complementary sections 4 and 5, each of which sections comprises a web 6 at the periphery of which is formed an enlarged annular casing 7. The casings 7 are preferably cylindrical in cross-section and their contiguous sides open toward each other, as clearly shown in Fig. 4. The webs 6 are provided with bearings 8, in which the shaft 1 is journaled and through which the same projects a sufficient distance beyond said webs for the reception of a suitable driving-pulley, and said bearings are provided with glands or stuffing-boxes 9 in order to exclude air from the interior of the casing.

The inner edges of the open sides of the chambers 7 are provided with oppositely-disposed inwardly-projecting annular lips 10, the outer edges of said openings being similarly formed and terminating in radially-extending flanges 11, which flanges are secured together in any suitable manner, but preferably through the medium of bolts 12, in order to provide a steam-tight joint therebetween.

The periphery of the disk 2 is provided at spaced intervals with notches or serrations 13, and fitting within said notches or serrations is a series of teeth 14, said teeth being carried by an expansible supporting-ring 15. It will be observed by reference to Fig. 4 that the disk 2 is provided at its peripheral edge with an outwardly-extending flange 16, which flange is formed integral with said disk and that the expansible supporting-ring 15 rests against said flange 16, so that the ring is prevented moving laterally by the flange 16, and it will also be observed that a detachable securing-ring 17 is mounted upon the side of the disk 2 opposite to the flange 16, so that said ring effectually holds the expansible ring 15 upon said disk. The ring 17 is held in fixed relation to the disk 2 through the medium of bolts 18, but it is obvious that any other desired securing means may be employed. By providing the expansible ring 15 with the teeth 14 and fitting said teeth within the notches or serrations 13 it is evident that a connection is made between said ring 15 and the disk 2, which will readily permit expansion and contraction of said ring 15 under the heat to which it is subjected incident to the passage of the steam and by providing the detachable securing-ring 17 it will also be seen that said ring 15 may be readily

removed from the disk 2 when such is desired.

Arranged upon the expansible supporting-ring 15 is a multiplicity of blades or vanes arranged to form an inner series 19 and an outer series 20, and the cross-sectional contour of said blades is substantially semicircular, as clearly shown in Fig. 5, whereby said blades are adapted to receive the impact of the steam as the latter is directed thereto. The length of the blades 19 and 20 is substantially the same as the size of the openings at the inner faces of the casings 7, and each of said blades is provided with an inwardly and outwardly extending lug 21, said lugs being formed upon the ends of said blades. It will be observed, however, that the lugs 21 at the inner ends of the blades 19 are seated in sockets formed in the outer face of the expansible supporting-ring 15, while the lugs 21 upon the outer ends of the blades 20 are seated in sockets formed in the inner face of a binding-ring 22, the lugs upon the outer ends of the blades 19 and the inner ends of the blades 20 being seated upon inwardly-extending ribs formed upon clamping-rings 23, arranged at the sides of said lugs and between the blades 19 and 20, said rings being suitably secured together. The lugs 21 are preferably square in order to prevent turning of the blades 19 and 20, and through the medium of the clamping-rings 23 and the binding-ring 22 it is obvious that said blades are firmly held upon the supporting-ring 15.

As before premised, it is one of the objects of the present invention to expand the steam as it is brought to the machine under boiler-pressure by a series of steps. This expansion in steps reduces the ratio of expansion in reducing the velocity of afflux. As the velocity of the moving blades should be about forty-six one-hundredths of the velocity of the issuing jet of steam, it is clear to be seen that this form of expansion in steps reduces the peripheral speed, and at the same time absorbs the whole kinetic energy by impact. For the purpose of producing high efficiency under varying loads I have deemed it expedient to introduce the steam to the turbine at a series of different points, four being shown as the preferable number, and admitting the steam at nearly full boiler-pressure and to arrange a series of exhausts at points intermediate of the inlets, so that the steam, after being introduced to the interior of the machine, may be expanded successively and finally exhausted, but not before the entire kinetic energy of the steam has been utilized.

In Fig. 2, the numerals 24 designate the inlets through which the steam is introduced from the boiler, which inlets are equidistant, and said inlets are suitably connected through piping 25 with the supply-pipe leading from the boiler. This supply may be controlled by a suitable throttling-valve, and each inlet

24 is provided with a suitable hand-valve 26, through the medium of which the introduction of the steam through the various inlets to the machine may be controlled in order 5 that the machine may be regulated for varying loads. It will therefore be seen that as the steam enters the inlets 24 the same passes into one of the casings 7, and in order to direct the live steam to the point of its first expansion said casing is provided opposite to each of said inlets with a passage 27, whereby the steam is conveyed to the opposite side of the casing, which is open and which is contiguous to the blades 19 and 20 of the rotating disk 2. In order to effect the expansion of the steam, a series of stationary admission-blades 28 is employed, which blades are formed upon a machined ring 29, seated within a rabbeted portion 30 of the inwardly-extending annular lip 10, a division-ring 31 being seated upon the outer ends of said blades and arranged intermediate the edges of said open side. Directly opposed to the admission-blades 28 and seated in a corresponding position in the open side of the other casing 7, is a series of stationary release-blades 32, formed upon a machined ring 33, seated in a rabbeted portion 34 of the lip 10 of the other casing 7, a division-ring 35 being arranged in the open side thereof and seated upon said blades 32. Fitted upon said division-ring 35 is a series of stationary admission-blades 36, said blades being formed upon a machined ring 37, seated in a rabbeted portion 38 of the outer lip of said casing. Directly opposed to the blades 36 in the other casing 7 and fitted upon the division-ring 31 is a series of stationary release-blades 39, which blades are formed upon a machined ring 40, fitted in a rabbeted portion 41 of the outer lip of said casing. It will thus be seen that the admission-blades of the two casings 7 are diagonally opposite to each other, while the release-blades are also 45 diagonally opposite, and it will also be noted that the spaces between the stationary blades 28, 32, 36, and 39 will communicate with the spaces between the blades 19 and 20, so that a continuous passage is formed between the two casings 7, and steam is permitted to readily pass from one to the other.

In Fig. 5 the exact construction of the admission-blades is shown and by referring thereto it will be observed that the same comprise a base-flange 42, from which extends a deflected flange 43. The flanges 43 are, however, each provided with a shoulder 44, and by reason of said shoulders it will be observed that narrow throats are formed between the blades, which throats gradually enlarge to the ends contiguous to the moving blades 19 and 20. Consequently the steam which is admitted to the mouths of said throat passes into the latter and after passing 60 the shoulders 44 begins to expand until the

blades 19 and 20 are reached, where that particular expansion ends, the steam passing then between the blades and between the release-blades directly opposite. In Fig. 5 the exact construction of the release-blades is 70 also shown and these also comprise base-flanges 45, from which extend curved flanges 46, the latter being curved in a direction reverse to the deflection of the flanges 43, so that after the steam passes through blades 19 75 and 20 the same is received between the blades 45 and effectually delivered thereby into the adjacent casing.

In order to accomplish the successive expansions of the steam hereinbefore referred to, it is necessary to transfer the steam in its progress around the casing 7 from one to the other, thereby following a substantially spiral path from the inlets to the exhausts, and to this end the casing 7, in which the inlets are 80 formed, is provided with a series of receiving-chambers, while the other casing 7 is provided with a series of return-chambers. The receiving-chambers gradually enlarge from the inlets to the exhausts, and at this point 85 it will be noted that the steam entering the inlets 24 is split at each one of the latter and flows from each side thereof to the next succeeding exhaust on either side. The steam, therefore, which passes through the passages 90 27 is expanded at the stationary admission-blades 28 at the end thereof, from which it passes into a receiving-chamber 47 directly opposite to said admission-blades. It then rises and passes through the admission-blades 95 36, where it receives its second expansion and is then returned to the receiving-chambers 48, formed in the casing 7, in which the inlets 24 are arranged. The chambers 48 are provided with inclined division-walls 49, 100 whereby the steam is gradually advanced around the periphery of the casing, and after this step the steam passes through the next set of admission-blades 28, where it receives its third expansion, and these steps continue 105 in succession until the adjacent exhaust is reached. The exhausts correspond in number to the inlets 24 and are designated by the numerals 50, said exhausts being formed in the casing 7 opposite to that wherein the inlets 24 are formed. The return-chambers 47 are likewise divided by means of division-walls 51, but said chambers 47 are arranged slightly out of alignment with the receiving-chambers 48 to insure a proper delivery of the 110 steam during its various traverses through the blades of the rotating element and during its advancement around the peripheries of the casings.

To provide for effectually superheating the 115 steam during the successive steps of expansion, each of the casings 7 is provided with a jacket 52, these jackets being filled with live steam introduced directly from the boiler, and the division-walls 49 and 51 are also 120 130

jacketed for the passage of live steam to further insure the proper superheating of the steam flowing in the machine. By referring to Fig. 5 it will be observed that the chambers 47 are each provided with projections 53 from the jackets 52, whereby a larger heating area is obtained.

It is highly desirable in the traverse of the steam through the machine, and from one chamber to another, to prevent splitting of the steam during the passage between the blades 19 and 20 and whereby the steam would not follow the regular course, and to the accomplishment of this end each of the stationary blades immediately contiguous to the walls 49 is of sufficient thickness to extend over and cover two of the moving blades, while each of the stationary blades immediately contiguous to the walls 51 is of sufficient thickness to extend over and cover three of the moving blades. Consequently the steam is precluded splitting as it passes from the receiving to the return chambers, and vice versa.

It has also been stated that one of the objects of the present invention is the provision of a joint between the movable and stationary elements of the turbine, which is adapted to prevent leakage or escape of the steam, and by referring to Fig. 4 this joint is clearly illustrated. The lips 10 are formed with inclined overhanging flanges 54, which flanges are inclined in the same direction or in the direction of the course of the steam, and said flanges correspond with beveled or chamfered surfaces formed upon the expansible supporting-ring 15. The clamping-rings 23 are likewise provided with similar flanges 55, said flanges corresponding with overhanging lips or flanges 56, formed upon the division-rings 31 and 35. The flanges 55 and 56 incline in the direction of the course of the steam through the blades 20 and are therefore reversed to the inclination of the flanges 54, and it will thus be seen that as the steam passes in both directions through the blades 19 and 20 the inclined flanges will prevent leakage through the clearance-spaces, a partial vacuum being formed therein, and consequently the interior of the machine between the webs 6 is freed from accumulations of the steam, which under ordinary circumstances is liable to escape through the clearance-spaces.

In Fig. 7 is shown another form of the invention; but in the main this is substantially the same as shown in the other figures. Fig. 7, however, discloses the use of a plurality of blades upon the rotating element, and by referring to said figure it will be observed that a pair of supporting-rings 57 is mounted upon the peripheral edge of the disk 2, each of said rings being provided with the inner blades 19 and the outer blades 20, the rings 57 being

held upon the disk 52 through the medium of bolts 58 or other suitable fastening devices. Interposed between the series of rotating blades is a series of stationary blades 59 and 60, corresponding to the blades 19 and 20, while the stationary admission and release blades shown in the other figures are employed in precisely the same relation in Fig. 6 as in the other form. It is also obvious that even a larger number of rotating blades may be employed; but Fig. 6 is deemed sufficient to illustrate this feature of the invention.

While the forms of the invention herein shown and described are believed to be preferable embodiments thereof, it will of course be understood that the same is susceptible of various changes in the form, proportion, and minor details of construction, and the right is therefore reserved to modify or vary the invention as falls within the spirit and scope thereof.

Having thus described my invention, what is claimed as new, and desired to be secured by Letters Patent, is—

1. In a turbine of the class described, a series of rotating blades, casings at the sides of said blades, and admission-blades arranged in said casings for introducing the steam to the rotating blades, said admission-blades having shoulders thereon to form throats which terminate in enlarged mouths adjacent to the rotating blades, whereby the steam is expanded during its passage between said admission-blades.

2. In a turbine of the class described, a series of rotating blades, casings at the sides of said blades, and admission-blades arranged in said casings for introducing the steam to the rotating blades, said admission-blades having shoulders thereon to form throats which terminate in enlarged mouths adjacent to the rotating blades, whereby the steam is expanded during its passage between said admission-blades, one of said casings having an inlet for the steam and the other provided with an exhaust.

3. In a turbine of the class described, a rotating element provided with a series of blades, a steam-casing arranged around said blades and having division-walls forming a connected series of spiral chambers around the periphery of the rotating element for advancing the steam in successive steps around said rotating element, and admission and release blades arranged in said casing adjacent to the blades of the rotating element.

4. In a turbine of the class described, a rotating element having a series of blades, and a casing having a steam inlet and exhaust, said casing being provided with a spiral-like passage extending on each side of said inlet around the peripheral portion of said rotating element and terminating at the steam-ex-

haust, whereby the steam introduced through said inlet is split and guided from each side thereof to the exhaust.

5. In a turbine of the class described, a rotating element provided with a series of blades, and a casing surrounding said element and formed of complementary sections each of which is provided with an annular steam-casing, said casings having open sides adjacent to the blades of said rotating element, and an expansible supporting-ring carried by said rotating element to which said blades are applied, and stationary admission and release blades arranged in the open sides 15 of said casings for effecting successive expansions of the steam during its traverse from said casings and through the blades of the rotating element.

6. In a turbine of the class described, a rotating element provided with a series of blades, a casing surrounding said element and comprising complementary sections each of which is provided with an annular steam-casing, said casings having open sides adjacent 25 to the blades of said rotating element and provided with jackets for the reception of live steam to effect superheating of the steam within said casings, and stationary admission and release blades arranged in the open sides 30 of said casings for effecting successive expansions of the steam in its traverse from said casings and through the blades of the rotating element.

7. In a turbine of the class described, a rotating element provided with a series of blades, a casing surrounding said element and formed of complementary sections each of which is provided with an annular steam-casing, said casings having their inner sides 35 open, a series of stationary admission and release blades arranged in the open sides of said casings for effecting successive expansions of the steam in its passage from said casings through the blades of the rotating element, one of said casings being provided with a plurality of inlets at spaced intervals around the same, and the other casing being provided with a plurality of exhausts around the same but arranged at points between said inlets, 45 and division-walls arranged in said casings and forming a connected series of spiral chambers, whereby the steam is successively advanced from the inlets to the exhausts.

8. In a turbine of the class described, a rotating element provided with a series of blades, a casing surrounding the same and provided with annular steam-chambers at opposite sides of the blades of said element, said chambers having their inner sides open, 55 stationary admission and release blades arranged in the open sides of said casings for effecting successive expansions of the steam during its passage from the chambers and through the blades of the rotating element,

one of said casings being provided with a plurality of steam-inlets and having a series of division-walls forming a series of connected chambers extending in opposite directions from each of said inlets, and the other casing being provided with a series of exhausts arranged at points intermediate said inlets, whereby the steam is expanded in a series of successive steps from the inlets to said exhausts. 65

9. In a turbine of the class described, a rotating element, an expansible supporting-ring mounted upon said element, an inner and an outer series of blades carried by said supporting-ring, steam-casings arranged at the sides of said blades and having their inner 80 sides open, stationary admission and release blades arranged in the open sides of said casings for effecting successive expansions of the steam as it passes from said casing through the blades of the rotating element, and a connected series of spiral passages arranged in 85 said casings for transferring the steam alternately between said casings during its passage therethrough.

10. In a turbine of the class described, a rotating element having its peripheral edge notched or serrated, an expansible supporting-ring mounted upon said element and provided with teeth or projections fitting within the notches or serrations thereof, means for securing said ring upon said element, a series 90 of blades arranged upon said supporting-ring, a steam-chamber surrounding said blades and having a steam-passage therein, and stationary admission and release blades arranged in 100 said casing for effecting successive expansions of the steam as it passes through said casing and the blades of the rotating element.

11. In a turbine of the class described, a rotating element, an inner and an outer series of blades carried by said rotating element, a binding-ring mounted upon the ends of the blades constituting the outer series, a steam-casing surrounding said blades, and stationary admission and release blades arranged in 105 said casing for effecting successive expansions of the steam as it passes through said casing and the blades of the rotating element. 110

12. In a turbine of the class described, a rotating element, an expansible supporting-ring mounted thereon, an inner and an outer series of blades arranged upon said supporting-ring, the blades of said series being provided with end projections or lugs, the lugs 120 upon the inner ends of the inner series being seated in said supporting-ring, a binding-ring arranged upon the outer ends of the outer series and provided with sockets for the reception of the lugs upon the outer ends of 125 said blades, clamping-rings embracing the lugs upon the outer and inner ends of the inner and outer blades, a steam-casing sur-

rounding the blades of the rotating element, and stationary admission and release blades arranged in said casing and adapted to effect successive expansions of the steam during its 5 passage through said casing and the blades of the rotating element.

13. In a turbine of the class described, a rotating element, an expansible supporting-ring carried thereby and detachably connected thereto and having an inner and an outer series of blades mounted thereon, a steam-casing surrounding the blades of the rotating element, stationary admission and release blades arranged in said casing and adapted to 10 effect successive expansions of the steam during its passage through said casing and the blades of the rotating element, division-walls arranged in said casing and forming a connected series of spiral chambers around the 15 blades of the rotating element, and jackets surrounding said casing and said walls for the reception of live steam to superheat the steam within the casing during the successive 20 expansions.

14. In a turbine of the class described, a rotating element having a series of blades, a casing having a steam inlet and exhaust, said casing surrounding said rotating element, a series of division-walls arranged in said casing 25 and forming a series of connected chambers arranged spirally around the axis of rotation, said chambers extending in opposite directions from the steam-inlet to the exhaust, whereby the steam introduced through said 30 inlet is split and guided from each side thereof to the exhaust, and admission and release blades arranged in said casing to successively 35

expand the steam in its passage through the casing.

15. In a turbine of the class described, a 40 rotating element having a series of blades, a casing having a steam inlet and exhaust, said casing surrounding said rotating element, a series of division-walls arranged in said casing and forming a series of connected chambers arranged spirally around the axis of rotation, said chambers gradually increasing in size from the inlet to the exhaust and extending in opposite directions from the steam-inlet to the exhaust, whereby the steam introduced through said inlet is split and guided 45 from each side thereof to the exhaust, and admission and release blades arranged in said casing to successively expand the steam in its 50 passage through the casing. 55

16. In a turbine of the class described, a rotating element having a series of blades, a casing associated with said rotating element and provided with admission and release blades for effecting expansion of the steam, a 60 series of inlets for admitting steam to said casing, a supply-pipe, branch pipes leading from said supply-pipe to said inlets, and means for controlling each inlet independent of the others, whereby the turbine may be 65 regulated in accordance with the variations in load and high efficiency maintained.

In testimony whereof I affix my signature in the presence of two witnesses,

JOHN W. SMITH.
